TYPEWRITING MACHINE

Willard C. Jones, Fairfield, and Walter James Gove, Wethersfield, Conn., assignors to Underwood Corporation, New York, N. Y., a corporation of Delaware

Application November 12, 1953, Serial No. 27,576

Term of patent 14 years

(Cl. D64—11)

To all whom it may concern:

Be it known that we, Willard C. Jones, a citizen of the United States, residing in Fairfield, in the county of Fairfield, State of Connecticut, and Walter James Gove, a citizen of the United States, residing in Wethersfield, in the county of Hartford, State of Connecticut, have invented a new, original, and ornamental Design for a Typewriting Machine, of which the following is a specification, reference being had to the accompanying drawing, forming part thereof.

Figure 1 is a front perspective view of a typewriting machine, showing our new design from the right-hand side thereof.

Figure 2 is a rear perspective view of the typewriting machine shown in Figure 1, the view being from the left-hand side thereof.

The dominant features of our design reside in the portion of the machine shown in solid lines.

We claim:

The ornamental design for a typewriting machine, as shown and described.

WILLARD C. JONES.

WALTER JAMES GOVE.
